United States Patent

Des. 241,739

Patented Oct. 5, 1976

241,739

TELEVISION CAMERA

Francis Arden Farey, Menlo Park, and Kenneth K. Lee,
Los Altos, Calif., assignors to Ampex Corporation,
Redwood City, Calif.

Filed May 21, 1975, Ser. No. 579,604

Term of patent 14 years

Int. Cl. D14—03

U.S. Cl. D16—1

FIG. 1

FIG. 2

FIG. 3

FIG. 4

FIG. 5

FIG. 1 is a top plan view of a television camera, showing our new design;

FIG. 2 is a right side elevational view;

FIG. 3 is a left side elevational view;

FIG. 4 is a front elevational view; and

FIG. 5 is a rear elevational view.

The bottom surfaces of the camera are substantially plain and unornamented.

We claim:

The ornamental design for a television camera, substantially as shown and described.
